COMMUNICATION SYSTEM

Charles R. Doty, Binghamton, N. Y., assignor to
International Business Machines Corporation,
New York, N. Y., a corporation of New York

Application November 28, 1936, Serial No. 113,102

8 Claims. (CL 178—33)

This invention relates to communication systems and more particularly to synchronous control systems, one well known type of which is the printing telegraph system.

An object of the present invention is the provision that two timed impulses are employed for all the character representations to be transmitted and received.

The present invention is an improvement and modification of the copending application Serial No. 54,390, filed December 14, 1935, and relating broadly to a two impulse system.

Another object of the present invention is the provision of individual rotary control means in place of the usual transmitting contacts associated with and controlled by the corresponding key bars.

Another object of the present invention is the provision of control means at the receiver conditioned by the first group of impulses to be operated at a later time in the operating cycle, and a second control means adapted to be conditioned by the second group of impulses and effective later in the timed cycle to effect selection of a single character circuit.

Still another object of the invention is the provision of means to provide overlap, whereby the first said control means may be conditioned by a second character signal while the second said control means is effective to select the circuit corresponding to the first character signal.

Still another object is a novel synchronizing device to establish phase correspondence.

Various other objects and advantages of the invention will be obvious from the following particular description of one form of mechanism embodying the invention or from an inspection of the accompanying drawings; and the invention also constitutes certain new and useful features of construction and combination of parts hereinafter set forth and claimed.

In the drawings:

Fig. 1 shows, in part, one type of transmitting and receiving control unit.

Figs. 2 and 3 show the transmitting and receiving rotary control devices.

Fig. 4 is a circuit diagram for the transmitting station.

Fig. 5 is a circuit diagram for the receiving station.

Referring to the drawings and in particular to Fig. 1, one form of a translating unit, such as the Electromatic typewriter, which may be used in the present system, will now be described briefly. In the embodiment illustrated in the

drawings, well known means are provided for actuating the type bars (not shown) by power operated devices comprising a power driven roller 10.

A cam 11 is pivoted on one arm of a bell crank lever 12 pivoted in the frame, the other arm of which is operatively connected with one arm of a bell crank lever 13 by means of link 14. The other arm of lever 13 is connected to the type bars (not shown) in a well known manner.

The lever 12 is actuated by the cam 11 when the latter engages the driven roller 10 to be operated thereby. The engagement of the cam 11 with the power roller is controlled by means of the key lever 17 in a manner which will now be described.

The cam 11 is resiliently engaged by a spring-pressed arm 20 which tends to turn it into engagement with the power driven roller or stop 21 on a lever 22 pivoted on the bell crank 12 and normally arranged in the path of a lug on the cam. When the lever 22 swings to move its stop out of the path of the lug, the arm 20 swings the cam into engagement with the power roller to be actuated thereby to swing the bell crank 12 to actuate its connected mechanism.

The lever 22 has an arm 24 which is provided with an offset projection 25 at its end which projects laterally through an opening in the bell crank 12 and engages the bifurcated lower end 26 of an arm 27 of a key lever 17 pivoted on the common rod 28.

It is obvious then that depression of a key lever 17 releases the revolvably mounted cam 11 to engage and be actuated by power roller 10 in turn operating bell crank 12 and its attached links to cause the associated mechanism, such as the key bars and other operating mechanisms, to be operated.

Attached to the key lever 17 is a connecting link 19 extending to a solenoid 18 disposed beneath the keyboard, so that upon energization of the said solenoid the connected key lever is depressed to operate the connected mechanism in the manner just explained.

In addition to actuating the several type bars and connected mechanisms, the revolvably mounted cams are adapted to open and close circuits which may be employed in the transmitting units. Upon release of the cam 11 the arm 30 is engaged thereby and displaced to the extent that the stop 31 attached thereto releases the dog 32, by releasing members 35 and 46. The arm 30 is latched in the said displaced position momentarily by means of the latch member 33. This

provision is made since the cam operation is not effective to displace the arm 30 to release the said dog for the predetermined timed interval required.

- 5 Dog 32 is pivotally mounted at 34 on member 35 which is attached to or may be an integral part of commutator or disk 36 (Fig. 2), said disk rotatably mounted on the shaft 37 which is rotated continuously by the commutator brush 10 shaft 38 through the reduction gearing 39. Secured to the shaft 37 is a notched clutch member 40 which is rotated continuously by the shaft, and is provided with two notches 41 adapted to be engaged by the dog 32. The said dog is urged 15 by spring 42 upon its release to engage the clutch member 40 and as the clutch member is rotated the dog and notched portion thereof engage to rotate the disk member 36 permitting the brushes 43 to engage the conducting portion of the disk. 20 It is noted that as the arm 35 is rotated it is adapted to knock out the latch 33, by means of pin 35a, thereby releasing the arm 30 and restoring the stop 31 to the normal position shown in Fig. 1, whereby it is effective to disengage the 25 dog from the clutch member 40, by blocking further rotation of the members 35 and 46. The member 46 is loosely mounted on the shaft 37 and is adapted to cause the dog 32 to be released from or engaged with the clutch member 40. 30 When the stop 31 is in the path of both members 35 and 46, member 46 forces the dog 32 out of engagement with the clutch member by rotating it partially about its pivot 34 thereby raising the dog out of the notch 41. Upon release 35 of the members 35 and 46 by stop 31, the spring 42 causes the member 46 to be rotated slightly, thereby permitting the dog 32 to engage the clutch member 40 and as the notch 41 is presented thereto, engagement of the dog and clutch member is effected.
- 40 The said clutch member is provided with two notches 41, therefore, upon the completion of a half revolution the clutch is disengaged to bring the disk 36 to rest. The disk is provided with two insulated segments 44 which are arranged 45 to engage the brushes 43 when the disk 36 is at rest. The disk 36 is adapted to be rotated one half of a revolution during one revolution of the transmitting commutator brushes 45 which are rotated by shaft 38. To provide for stopping and releasing the clutch every half revolution, the members 35 and 46 are extended similarly at each end thereof so as to be engaged and blocked or released by the stop 31 in the manner just described.

55 It will be understood that the usual number of key bars and power devices with their associated mechanisms are provided, but only one of them is shown for the sake of simplicity. It is obvious, therefore, that for a simplex system operation the transmitting unit may comprise the device just described including the cam operated clutch arrangement, and for the receiving unit, the device described may be used as shown including the connecting solenoids.

60 Referring now to Fig. 4, the developed commutator 50 is shown to be provided with twenty conducting segments 51, two main groups of segments 51-1 to 7 and 51-8 to 14 employed 65 for the transmission of the character impulses and an additional segment 51-15 employed for the transmission of periodic pulses for synchronizing purposes. The segments 51-1 to 7 and 51-8 to 14 are connected in combination to the 70 various rotary clutch brushes 43, so that upon

the release of an individual clutch by the character key of the typewriter unit two differently timed impulses are transmitted to the line 52 as the transmitting commutator brushes 45 pass over the segments 51 thereof.

75 For example, assume that the character key bar A is depressed, releasing the associated cam 11 to operate the associated clutch member and disk 36, it is seen in Fig. 2 that engagement of the dog 32 and member 49 is effected at a time 10 when the brush 45 passed over the synchronizing segment 51-15 so that shortly after the brushes 43 leave the insulated segment 44, the brush 45 is in position to engage segment 51-1 and the other transmitting segments progressively; in this manner the proper time values are always imparted to the character signals.

80 Release of the clutch disk 36 for character A conditions the segments 51-2 and 51-3; that is, the said segments are now active segments 20 for a predetermined timed interval which is equivalent to one revolution of the transmitting brushes 45. Therefore, as the brush 45 passes over the first segment 51-2, a signal condition is set up by the following circuit, one side of the 25 line by common conductor 53 is connected to one of the brushes 43 and due to the conducting portion of the disk 36 is now connected to the remaining brushes 43, whereby, at this particular interval, the said line is connected to conductor 30 54, segment 51-2, brushes 45, common conducting ring 55 to the other side of the line by conductor 56, energizing the lines at this timed interval. As the brush 45 progresses to segment 51-3, one side of the line is now connected to conductor 57 to complete the circuit through the 35 said segment again energizing the line.

40 It is seen, for each revolution of brushes 45, a synchronizing impulse is transmitted over the line as the brushes pass over segment 51-15.

45 Referring now to Fig. 5, a segmented commutator 60 is provided and similar to the transmitting distributor 50, twenty segments 61 are provided and arranged in groups as previously described. Additional segments 62 are provided to properly phase the receiving distributor motor 63 so as to operate in phase and synchronism with the transmitting distributor motor (not shown). Assume that only the synchronizing impulses are transmitted and that the receiving system is just connected to the line by closed switch 64 to engage contacts A. If the synchronizing impulses are received as brushes 65 pass over the synchronizing segment 61-15, the signal 66 is energized to indicate the condition of 50 synchronism; however, in the event that the synchronizing pulses are received as the brushes 65 pass over any of the segments 62, the relay 67 is energized to open the associated contacts 68 momentarily.

55 The purpose of opening one side of the line to the synchronous motor 63 is to cause the motor to slip a pole, thereby adjusting the brush position of the receiving distributor with respect to the brush position of the transmitting distributor. To limit the pole slipping to one pole per operation of relay 67, a resistance 69 is placed across the contacts 68 so as to be included in series in the motor supply circuit when contacts 68 are opened. When synchronism is obtained, 70 the signal 66 is energized indicating the fact and switch 64 now is positioned to engage contact B conditioning the system for operation of the translating units.

75 The first group of character signals transmit-

ted is provided to energize the controlling solenoids 70 (Fig. 3) to release rotary clutches 14 which are released and stopped in exactly the same manner as the clutches described in the transmitter. The energization of solenoid 70 displaces the arm 71 to release the dog 72 to engage the clutch member 73 near the end of the distributor cycle to rotate the conducting disk 74 closing the circuits associated with the 10 brushes 75; therefore, to continue with the assumed example, the first impulse for character A is received as the distributor brushes 65 pass over segment 61—2 to complete the following circuit, conductor 76, a collector ring 77, brushes 15 65, segment 61—2, conductor 78, solenoid 70—a, conductor 79 and switch 64 to conductor 80 representing the other side of the incoming line. Energizing of solenoid 70—a releases the clutch disk 74—a to connect the corresponding brushes 20 75—a to the associated circuits; however, it must be understood that the dog 72 does not engage the notch or tooth of the clutch member 73 (Fig. 3) to rotate the disk 74—a until later in the said cycle, that is, approximately when the distributor brushes 65 pass the segment 61—13 as 25 shown in the figure.

The second group of impulses of the character signals are received on segments 61—8 to 14 to control the charging of condensers 81, the purpose of which will be understood as the description progresses. The second impulse for the character A is received as brushes 65 pass the distributor segment 61—8 to charge the condenser 81—a as follows: conductor 76, collector 30 ring 77, brushes 65, segment 61—8, conductor 82, condenser 81—a, conductors 83 and 79, switch 64 to conductor 80, charging the condenser. Attached to the distributor brush driving shaft 84 (Fig. 3) is a control ring 85 provided with two 35 conducting segments 86 and 87. Conducting segment 86 is arranged so that during the rotation of the control ring 85 it is adapted to engage brushes 88—a and 88—b and conducting segment 87 at a later interval in the cycle is adapted to 40 engage brushes 88—b and 88—c. Conducting segment 86 is adapted to engage the associated brushes at a time in the cycle approximately when the distributor brushes 65 pass over the segment 61—15. The length of the said segment 45 may be varied, the only provision being that it must be of such length to permit the discharge of the associated condenser 81 to be effective to energize the particular character key solenoid selected; the segment 87 then engages the 50 associated brushes a short timed interval later in the cycle.

As the segment 86 engages the brushes 88—a and 88—b, the condenser 81—a just charged is now arranged to discharge through a particular character solenoid to effect the selection of a particular character key bar solenoid from a group of solenoids that are connected to the brushes 75—a associated with the clutch disk 74—a. The discharge circuit for condenser 81—a is as follows: condenser 81—a, conductor 89, brush 88—b, conducting segment 86, brush 88—a, common conductor 90, solenoid 18 for character key bar A, conductor 91, brushes 75—a, common return conductors 92 and 79 to the condenser, 70 thereby energizing solenoid 18 for the character A. The other solenoid circuits for characters Z, Q, and W, etc., are not affected since the associated brushes 75—a are engaging the insulated portion of clutch disks 74—a. The segment 87 75 then engages brushes 88—b and 88—c to short

circuit the condenser 81—a through resistance 83 so as to avoid the possibility of any charge remaining in the said condenser so as to prevent a faulty energization of any solenoid circuits in the following cycles.

It is evident from the description just set forth how the other character selections may be effected and further detailed description thereof is deemed not necessary. It is also seen that during the condenser discharge operation to energize the solenoids 18 and effect total discharge of the condenser, the first group of signals to energize the rotary clutch solenoids 70 may be received on segments 61—1 to 7, thus providing a certain degree of overlap in the system.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. A communication system comprising a plurality of control circuits, and receiving means responsive to character signals comprising control means to select a predetermined number of control circuits and means including electrostatic discharge means to discharge through a particular circuit of said selected group to effect selection of a single circuit from the said predetermined number of circuits.

2. A communication system comprising means to receive character signals to effect a selection of a single circuit from a plurality of circuits comprising control means to select a predetermined number of circuits from said plurality of circuits, and means including a condenser to discharge through one of said predetermined number of circuits for effecting the selection thereof.

3. A communication system comprising a plurality of control circuits, and receiving means responsive to a plurality of character impulses during a predetermined time interval including control means conditioned by the first impulses received at a certain time in said timed interval and operated at a later time in said interval and a second control means including an electrostatic discharge device energized by the second impulses received at a certain time in said interval and effective for discharge at a later time in the same to cause selection of a single circuit from said plurality of control circuits.

4. A communication system comprising, in combination, means comprising cyclically operating rotary distributor means for receiving control signals represented by a plurality of impulses during one cycle thereof, a plurality of control circuits, control means conditioned by the first impulse received during the cycle and operated at a later time in the cycle to select a predetermined number of said control circuits, and a second control means energized by a second impulse received during said cycle and effective during part of the following cycle to effect selection of a single circuit from said predetermined number of circuits selected.

5. A communication system, comprising, in combination, means to receive control signals, a plurality of control circuits, control means responsive to said signals to select a predetermined number of said control circuits, and a second

control means including means responsive to said signals and operated under control of the first mentioned control means to effect a selection of a single circuit from said predetermined number of circuits.

6. A communication system comprising, in combination, a plurality of control circuits, means to receive control signals, control means responsive to said signals to select a predetermined number of circuits from said plurality of circuits, condensers charged by said control signals, and means to discharge said condensers at a later timed interval to effect selection of a single circuit from said predetermined number of circuits selected.

7. The invention set forth in claim 6 in which

means are provided to discharge the said condensers a second time before being charged by the said control signals.

8. A communication system comprising, in combination, means to receive control signals, circuit selecting means conditioned by said signal and control means energized by said signal, means whereby both the circuit selecting means and control means are operated at a later time to effect the circuit selecting operation, and means to condition the circuit selecting means by a second signal while the said control means is effecting the circuit selecting operation in accordance with the first mentioned signal.

CHARLES R. DOTY.
